UNITED STATES PATENT OFFICE.

ARTEMAS M. BROWN, OF OTTAWA, OHIO.

WHEEL-HUB.

SPECIFICATION forming part of Letters Patent No. 295,728, dated March 25, 1884.

Application filed December 15, 1883. (No model.)

To all whom it may concern:

Be it known that I, ARTEMAS M. BROWN, a citizen of the United States, residing at Ottawa, in the county of Putnam and State of Ohio, have invented certain new and useful Improvements in Wheel-Hubs; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is partly a side view, partly a vertical section. Fig. 2 is also partly in section, and shows the finished hub. Fig. 3 is a perspective view of one of the rings. Fig. 4 is an enlarged sectional view of a portion of the ring.

This invention relates to wheel-hubs in which the wooden portion is strengthened by one or more solid metallic bands compressed in annular grooves turned in the periphery; and it consists in the construction and novel arrangement of devices, as hereinafter set forth, and particularly pointed out in the appended claim.

In the accompanying drawings, the letter A designates a wooden hub, which is first reduced to a diameter nearly equal to that of the finished hub, and is provided with two annular grooves, B, which are turned in the peripheral portion of the hub, one near each end. These grooves B are of rectangular form in cross-section, and of proper depth and width to receive the inner or base ribs of metallic strengthening-bands C, of corresponding dimensions. These bands are designed to be arranged at the proper distance apart to admit of the introduction of the ends of the spokes between said bands. The band C is of annular form, and without seam or joint. It is made with an annular interior rib or fillet, D, and with a broad outer portion, E, from the middle portion of which said rib or fillet projects inward, so that a continuous overlapping lateral flange, F, is provided on each side of the rib, said flange having its inner surface beveled from the base of the rib outward to

the point i, and terminating in a short and sharp bevel, Z, which joins the outer surface in a sharp edge, so that it can be easily forced into the superficial portion of the hub, even with the same, the bent fiber of the wood easily conforming to the short bevel Z, so that the edge of the band and the surface of the wood will fit together without breaking the fibers of the wood.

In the unfinished state of the hub, the seamless metallic bands are placed over the annular grooves, and, being held in this position, are subjected to mechanical compression, forcing them bodily inward at all points, until their ribs enter the annular grooves and their flanged outer portions are forced into the wood of the hub even with the peripheral surface thereof, the sharp edges of the flanges, by reason of the short bevels, meeting and joining neatly with the peripheral fibers of the wood, which easily conform thereto. The object to be accomplished is to strengthen the wheel-hub, not only in its central part between the bands, where the mortises are made and the ends of the spokes are inserted, but also, and more particularly, to strengthen the ends of the hub, so as to prevent splitting or checking outside of the bands and toward the ends of the hub. The grain or fiber of the wood at each side of the rectangular groove, which is liable to become loosened and to rise by the action of atmospheric moisture and abrasion, is protected by the lateral overlapping flanges of the band, which lock the fiber ends in place, and prevent, to a great extent, the access of moisture. In this manner great strength and solidity are given to the hub. After the strengthening-bands have been compressed into the hub, the latter is again placed in the lathe and finished in proper shape to receive the point and butt bands.

Having described this invention, what I claim, and desire to secure by Letters Patent, is—

The combination, with the wooden wheel-hub having turned into its periphery annular grooves of rectangular form in cross-section, of the metallic seamless bands C, having the interior rectangular annular rib or fillet, D, and the broad outer portion, E, the said rib 95 100

having a beveled flange, F, on both sides thereof, extending from its base to the point *i*, and terminating in a short and sharp bevel, Z, which joins the outer surface of the band in a sharp edge, whereby the bands can be easily forced into the grooves in the hub even with the seain, the fibers of the wood made to conform to the said short bevels Z, and the edges of the band and the fibers of the wood will

fit together without breaking the fibers of the latter, substantially as and for the purposes specified.

In testimony whereof I affix my signature in presence of two witnesses.
